(**) Term: **14 Years**

CLAIM

(21) Appl. No.: **29/145,882**

The ornamental design for a removable cover for a glucose meter, as shown and described.

(22) Filed: **Jul. 31, 2001**

DESCRIPTION

(51) LOC (7) Cl. **24-01**
(52) U.S. Cl. **D24/169**
(58) Field of Search D24/169; 600/316,
600/322, 323, 326, 347, 365, 366, 368

(56) **References Cited**

FIG. 1 is a perspective view of a removable cover for a glucose meter, showing our new design;

U.S. PATENT DOCUMENTS

FIG. 2 is a front view thereof;

D371,198 S * 6/1996 Savage et al. D24/169
D392,740 S * 3/1998 Yung et al. D24/169

FIG. 3 is a rear view thereof;

FIG. 4 is a side view thereof;

FIG. 5 is a side view thereof, opposite that shown in FIG. 4;

FIG. 6 is a top plan view thereof; and,

FIG. 7 is a bottom plan view thereof.

The broken line shown of the glucose meter is for illustrative purposes only and forms no part of the claimed design.
